UNITED STATES PATENT OFFICE.

LUDWIG STUEFEE, OF CINCINNATI, OHIO.

HOSE-CO尤PLING.

SPECIFICATION forming part of Letters Patent No. 772,975, dated October 25, 1904.

Application filed July 9, 1904. Serial No. 215,877. (No model.)

To all whom it may concern:

Be it known that I, LUDWIG STUEFEE, a citizen of the United States, residing at Cincinnati, in the county of Hamilton and State of Ohio, have invented certain new and useful Improvements in Hose-Couplings; and I do hereby declare the following to be a full, clear, and exact description of the invention, such as will enable others skilled in the art to which it applies to make and use the same.

My invention relates to improvements in hose-coupling.

One of its objects is to provide a simple and reliable coupling which is quickly connected or disconnected and which is not liable to injury when being drawn over the ground.

Another object is to provide a coupling with a swivel-joint, so that the hose will straighten itself or can be straightened without uncoupling the joints.

It further consists in certain details of form, combination, and arrangement, all of which will be more fully set forth in the description of the accompanying drawings, in which—

25 Figure 1 is a central vertical section through my improved coupling on line $v-v$ of Fig. 3. Fig. 2 is a plan view of the same. Fig. 3 is a section on line $z-z$ of Fig. 2. Fig. 4 is a plan view of one of the coupling-sections detached. Fig. 5 is a plan view of the opposite coupling-section, showing the reverse side from Fig. 2.

A represents the male, and B the female, section of the coupling, and D the hose-sections, which may be secured thereto in any approved manner. The meeting ends of the two sections are preferably beveled, so that one fits tightly within the other, and may be provided with an elastic packing-ring or not, as desired. Projecting from one side of the section B is a tongue B', to the opposite sides of which are hinged the clamping-sections E F, the three parts B' E F forming a ring which embraces and locks the section A in its 45 adjusted position relative to the section B. In order to insure this locking action, the

section A is provided with a raised annular rib G, which seats in a corresponding groove g in the parts B' E F. A spring-arm or strap H is secured either to one of the hinged sections E F, as indicated in full line in Fig. 5, or preferably to the tongue B', as indicated in Fig. 3, and its free end provided with an opening h to pass over the stud i to lock the free ends of the hinged sections together. 55

The action of the rib G and groove g is such as to force the two coupling-sections together and at the same time permit the section A to swivel or be turned relative to the section B, so that kinks or twists may be taken from 60 the hose without uncoupling the same. By employing a broad tongue B', rigidly connected to the coupling member B, this tongue takes the major part of the strain, thereby relieving the hinged sections from undue strain. 65

The coupling herein shown and described is capable of considerable modification without departing from the principle of my invention.

Having described my invention, what I claim is—

1. In a hose-coupling, a coupling member having a seating-face and an external annular rib, a coupling member having a registering seating-face, a tongue projecting beyond said face, clamping-sections hinged at opposite sides of said tongue, a groove in said tongue and clamping-sections to receive the rib of the opposite coupling member, and means for locking said clamping-sections over said rib. 75 80

2. In a hose-coupling, a coupling member having a seating-face and an external annular rib, a coupling member having a seating-face to register with that of the opposite coupling member, a tongue projecting beyond said face, clamping-sections hinged at opposite sides of said tongue, a groove in said tongue and clamping-sections to receive the rib of the opposite coupling member, and a spring-arm adapted to engage a stud on one of the clamping-sections to lock the free ends of the clamping-sections together. 85 90

3. In a hose-coupling, a coupling member having a seating-face and an external rib, a coupling member having a seating-face to register with that of the opposite coupling member, a tongue of substantially one-third of the circumference of the coupling member projecting beyond said seating-face, clamping-sections hinged at opposite sides of said

tongue, and means for locking the free ends of said clamping-sections together.

In testimony whereof I have affixed my signature in presence of two witnesses.

LUDWIG STUEFEE.
